(57) **CLAIM**

The ornamental design for a bottle, as shown and described.

DESCRIPTION

FIG. 1 is a front left side perspective view showing the new design for a bottle;

FIG. 2 is a rear right side perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof;

FIG. 9 is a front left side perspective view thereof taken from underneath the design; and,

FIG. 10 is a rear right side perspective view thereof taken from underneath the design.

The dotted broken lines in-the-FIGS, shown illustrate portions of the bottle and form no part of the claimed. The dash dot broken lines represent a boundary and form no part of the claimed design.

1 Claim, 10 Drawing Sheets
